UNITED STATES PATENT OFFICE.

WILLIAM H. BARROWS, OF BROOKLYN, NEW YORK, ASSIGNOR TO THE
BROOKLYN RAILWAY SUPPLY COMPANY.

STREET-SWEEPER.

SPECIFICATION forming part of Letters Patent No. 423,718, dated March 18, 1890.

Application filed June 4, 1888. Serial No. 276,033. (No model.)

To all whom it may concern:

Be it known that I, WILLIAM H. BARROWS, a citizen of the United States, and a resident of Brooklyn, Kings county, New York, have 5 invented certain Improvements in Street-Sweepers, of which the following is a specification.

My invention relates to that class of sweeping-machines known as "street-sweepers," 10 and which employ a revolving broom driven through the ground-wheels of the machine; and my object is in part to improve the means employed for suspending the broom and in part to improve the disengaging gear 15 or device.

My invention will be fully described hereinafter, and its novel features carefully defined in the claims.

In the drawings which serve to illustrate 20 my invention, Figure 1 is a plan of a sweeper embodying my improvements, a part of the platform or bed of the vehicle being broken away to show the mechanism below it. Fig. 2 is a side elevation of the main portion of 25 the sweeper, the near wheel of the vehicle being removed and the hub thereof shown in section. Fig. 3 is an enlarged detail view of the disengaging mechanism, which will be hereinafter described.

30 A is the platform or bed of the vehicle. B B are the ground-wheels.

C is the axle, which is rotatively mounted in bearings a a on the frame of the bed, and D is the broom arranged under the bed and 35 obliquely to the axle C.

E is a shaft mounted rotatively in bearings under the platform A. This shaft stands obliquely to the axle and substantially parallel with the axis of the cylindrical broom. 40 F is a U-shaped bar, in the short branches b b of which the journals c c of the broom are provided with bearings.

The broom is adapted to be raised and lowered, (as in other machines of this character,) 45 so that the driver may lift the broom clear of the ground when driving to and from his work.

To couple the broom to the vehicle and yet allow it to be raised and lowered, I provide

50 at its forward or advanced end a swinging arm G, secured rigidly at one end to the bar F at a point near the journal-bearing of the broom and mounted on the shaft E at its other end. The shaft E turns freely in the eye or bearing in the end of arm G. I could of course hinge the end of arm G directly to the platform; but the end of shaft E provides a convenient hinging-point, and it enables the broom to swing, in rising and falling, concentrically about said shaft E. 55

At the rear end of the broom I provide another swinging arm H, which is in the shape of a Y, the two branches d d of which are rigidly secured to bar F, and the body of which is hinged to the platform inside of the 60 ground-wheel on that side through the medium of a hinge-plate e, secured rigidly to the frame of the platform. It will be noted as an important feature that this Y-shaped arm H is constructed in such a manner as to 65 be very stiff in proportion to its weight, and that by employing it in connection with the bar F, as seen in Fig. 1, I am enabled to bring the hinging-point, at e, inside of the ground-wheel, notwithstanding the journal of the 70 broom projects at this end out laterally into the track of said wheel. I thus avoid the heavy and cumbersome construction sometimes employed, wherein the support for this 75 end of the broom extends across and exterior to the ground-wheel. In the construction shown in Fig. 1 the two hinge-centers upon which the broom swings when it is raised and lowered are at substantially the same distance from the axis of the broom measured 80 radially of the broom.

The broom is adapted to be raised and lowered simultaneously and uniformly at both 85 ends by a system of levers controlled by the driver. On the platform A is mounted the seat I of the driver. Its position is indicated in Fig. 1 by dotted lines. Under this seat on the top of the platform is arranged the primary lifting-lever J, the forward end f of which may be depressed by the driver's foot. J' is the secondary lifting-lever, which lifts 90 the forward end of the broom. This lever is fulcrumed at g on the under side of the plat- 95

form, and is coupled by a link h to the primary lever at one end and by a link i to the bearing of the forward end of the broom. J^2 is the secondary lifting-lever, which lifts the 5 rear end of the broom. This lever is fulcrumed at g' to the under side of the bed, and is coupled at one end to the primary lever by a link h' and at its other end to the bearing of the rear end of the broom by a 10 link i' . The primary lever is provided with a counter-weight h , which may be adjusted along the lever in such a manner as to nearly balance the weight of the broom and its attachments. In order to adjust the levers 15 properly with respect to the broom, the links i i' , which are or may be exactly alike, are each provided with a swivel-link i^2 , as seen in Fig. 2, which enables the length of the link to be varied within limits. The purpose of this 20 is to enable the broom to be adjusted to suit the surface to be swept—that is, if the broom becomes worn off more at one end than the other the worn end of the broom may be lowered. It will suffice if only one of the links 25 i or i' be provided with this adjusting device; but it is preferable to use links of the same kind at both ends of the broom.

I will now describe the mechanism for communicating rotary motion to the broom from 30 the ground-wheel. The ground-wheels B B drive the axle, operating in this respect precisely as though they were rigidly secured to the axle. However, in order to permit of turning the vehicle, I ratchet the wheels on 35 the axle in a well-known way and as illustrated in Fig. 2—that is to say, there is a ratchet-wheel, as j , fixed on the axle within the hollow of the wheel-hub, and a spring-pawl, as j' , carried by the hub, engages said 40 ratchet-wheel. On the axle is secured a bevel-wheel K , and on the shaft E is a bevel-wheel L , which meshes with wheel K . Thus the axle drives shaft E . On the shaft E is a sprocket-wheel m , and on the journal at the forward 45 end of the broom is a similar sprocket-wheel n . Over these passes an endless sprocket-chain o , through which shaft E drives the broom. Thus the axle C imparts its rotary motion to the broom D , and it would do this when 50 the broom was raised from the ground as well as when it was lowered. I provide means, however, whereby the driver may at will disengage the wheel L from wheel K , and this device I will now describe with especial reference to Fig. 3. The wheel L , which will 55 usually be a pinion, is splined on shaft E , and is thus adapted to be moved along said shaft out of engagement with wheel K . To enable the driver to conveniently effect this disengagement, the long boss of wheel L is provided 60 with a circumferential groove where it is embraced by a fork on a shifting-lever p , fulcrumed in a socket q , set in the platform A . The free end of lever p projects up through 65 the socket q and is within reach of the driver's hand. The socket q projects up somewhat

above the upper surface of the platform and is flared to permit the lever to play, the sides of the flared socket serving as stops to limit said play. To hold the lever in each of its 70 positions—that is, when the wheel L is in engagement and when it is out of engagement—I provide a flanged cap-plate r , which has an aperture in it through which the lever passes and in which it loosely plays. This cap-plate 75 has also at its opposite ends flanges $r' r'$, one or the other of which takes over the margin of the flared socket and holds the lever in the position set. When the driver wishes to engage or disengage the wheels K L , (as the case 80 may be,) he lifts the plate r , shifts the lever p , and drops the plate again.

In order to protect the shaft and spline against accumulations of mud when the broom is at work, I provide a tubular protecting sleeve-like shield s , (see Fig. 3,) which embraces the boss of wheel L at one end and is secured thereto, so that it moves along longitudinally with the said wheel in shifting. This shield plays over a collar t on 90 shaft E , said collar serving to close the end of the shield and keep out mud and dust. I prefer to make this tubular shield of sheet metal of cylindrical form and to rivet or screw it to the boss of wheel L ; but this mode of 95 constructing it is not essential. It may be made of cast metal, for example, and, if desired, it can be integral with the wheel-boss. I usually provide the other journal of the broom with a sprocket-wheel n' , precisely 100 like the sprocket-wheel n . The object of this is to enable the broom to be conveniently taken out of its bearings and turned end for end. This will sometimes be advisable when the broom is inclined to wear away more at 105 one end than at the other.

The broom is not designed to be lifted very high, and in order to avoid elevating the platform A and axle C too far above the ground I usually arrange the axle to stand 110 only a very little above the surface or crown of the broom when the latter is new and rests on the ground. When the broom is raised, the brush-like surface will yield at the point where it comes in contact with the axle. 115

It will be understood that in my sweeper the broom is driven from the axle precisely as if the wheels B were rigidly secured on the axles, and I only adopt the well-known ratcheting of the wheels for the reasons explained. 120

Having thus described my invention, I claim—

1. In a sweeper having a revolving broom capable of being raised and lowered, the combination, with the platform of the sweeper, the said broom, and the lifting-levers, of the links connecting the ends of the secondary levers with the brooms, one of said links being provided with a swivel for varying its length, as set forth. 125
2. In a sweeper, the combination, with the 130

platform and the shaft E, mounted in bearings under the same, of the gear-wheel L, splined on said shaft E and provided with a grooved boss to receive the fork of the shifting-lever, the said shifting-lever, the flared socket in which the shifting-lever is fulcrumed, and the flanged cap-plate r, constructed and operating as set forth.

In witness whereof I have hereunto signed my name in the presence of two subscribing witnesses.

WILLIAM H. BARROWS.
